UNITED STATES PATENT OFFICE.

ALFRED ARNT, OF BAINBRIDGE TOWNSHIP, BERRIEN COUNTY, MICHIGAN, ASSIGNOR
OF ONE-HALF TO EDWARD HENDRICKS, OF BENTON HARBOR, MICHIGAN.

EXTENSIBLE CAR-STEP.

1,172,188.

Specification of Letters Patent. Patented Feb. 15, 1916.

Application filed July 7, 1915. Serial No. 38,515.

To all whom it may concern:

Be it known that I, ALFRED ARNT, a citizen of the United States, residing in Bainbridge township, in the county of Berrien 5 and State of Michigan, have invented new and useful Improvements in Extensible Car-Steps, of which the following is a specification.

This invention relates to improvements in 10 extensible car steps and has particular application to a manually controlled step.

In carrying out the present invention, it is 15 my purpose to provide an extensible car step which may be used in conjunction with the usual stationary steps so that an additional step may be provided whenever necessary to facilitate the descent of passengers from the platform of the car and the ascent of passengers to such platform.

20 It is also my purpose to provide an extensible car step wherein the step will be normally held in elevated or inactive position against the bottom of the lowermost stationary step, and which may be readily 25 and quickly lowered to an active position whenever desired or necessary.

A further object of my invention is to provide an extensible car step wherein the step 30 may be securely and effectively locked in elevated or inactive position and wherein the component parts of the locking means will be so arranged and correlated as to reduce the possibility of derangement to a minimum.

35 With the above and other objects in view, the invention consists in the construction, combination and arrangement of parts hereinafter set forth in and falling within the scope of the claims.

40 In the accompanying drawings, Figure 1 is a fragmentary side elevation of a railway car platform equipped with an extensible step constructed in accordance with the present invention, the step being shown in lowered position. Fig. 2 is a fragmentary cross sectional view through the same. Fig. 45 3 is a vertical sectional view approximately on the line 3—3 of Fig. 1. Fig. 4 is a horizontal sectional view on the line 4—4 of Fig. 50 2. Fig. 5 is a vertical sectional view through the operating means and the locking mechanism therefor.

Referring now to the drawings in detail, 1 designates a set of steps depending from

the platform of a railway car and of any 55 suitable or approved construction. Fastened to the outer surfaces of the side members of the steps are casings 2, 2 respectively, each comprising side walls 3, 3 spaced apart in parallelism and front and back edge walls 60 4, 4. Slidably mounted within each casing 2 and adapted to be moved into and out of the casing through the lower end thereof is a rack bar 5 and connected with the lower extremities of the rack bars 5 is an extensi- 65 ble step 6. In the present instance, the teeth of the rack bars 5 face the rear edge walls 4 of the respective casings and formed on the rear edge walls of the casings and project- 70 ing rearwardly therefrom are casing exten- 75 sions 7 in open communication with the respective casings 2, 2 and journaled in the side walls of the extensions 7 is a shaft 8, while keyed upon the shaft 8 and disposed within the respective extensions 7 are pin- 80 ions 9 meshing with the rack bars 5 and adapted to elevate the rack bars when the shaft 8 is rotated in one direction to move the extension step 6 up against the bottom stationary step, and to lower said step 6 to active position when the shaft is rotated in the opposite direction.

In order to limit the downward movement 85 of the step 6 and hold the step against accidental movement when occupied, the rear edges of the rack bars 5, below the teeth thereon, are formed, with outwardly projecting lugs 10 respectively that are adapted to engage lugs 11 on the rear edge wall of the casing in the path of movement of the lugs 90 10. Also formed on the rear edges of the respective rack bars above the rack teeth thereon are lugs 12 adapted to be engaged by the adjacent teeth of the pinions when the step is lowered to cause a binding action 95 between the rack bars and pinions, the teeth on the pinions engaging the lugs 11 acting to force the forward edges of the rack bars into engagement with the front edge walls 4 of the casings 2 so as to augment the action 100 of the lugs 10 and 11 and so insure the step against accidental downward movement.

Keyed upon the shaft 8 is a bevel pinion 13 meshing with a similar pinion 14 fast upon the lower end of a vertical shaft 15 105 journaled in suitable vertically alining bearings 16. The upper end of the shaft 15 terminates in a casing 17 fastened to an appro-

priate part of the car body and journaled in the casing 17 at right angles to the shaft 15 is a shaft 18 upon which is secured a bevel pinion 19 meshing with a similar pinion 20 on the shaft 15 so that when the shaft 18 is rotated a like motion will be imparted to the shaft 15 and so rotate the shaft 8 to move the extensible step. Fixed upon the outer end of the shaft 18 is a crank disk 21 adapted 10 to be rotated by hand to revolve the shaft 18. The rear face of the crank disk 21 is disposed in confronting relation with the adjacent end wall of the casing 17 and formed in such face of the crank disk is a recess 22, while fixed upon the top wall of the casing 17 is a guide frame 23 in which is slidably mounted a bolt 24. Surrounding the bolt 24 is an expansion spring 25 having one end bearing against one end wall of the 20 frame and the remaining extremity abutting a collar 26 fixed upon the bolt 24. This spring acts to throw the bolt 24 normally to locking position into the recess 22 to lock the crank disk 21 against movement and so 25 hold the shafts 18, 15 and 8 against rotation and the step 6 in elevated or inactive position.

27 designates a bracket mounted upon the upper wall of the casing 17 and fulcrumed 30 upon the bracket 27 is a lever 28 having the lower end pivotally connected with the rear end of the bolt 24 and the upper end equipped with a handle 29. By means of the lever the bolt may be retracted from the recess 22 35 to release the crank disk or hand wheel 21 and when the hand wheel or crank disk is relieved of the influence of the locking bolt, such disk may be rotated to lower the step.

While I have herein shown and described 40 one preferred form of my invention by way of illustration, I wish it to be understood that I do not limit or confine myself to the precise details of construction herein described and delineated, as modification and 45 variation may be made within the scope of the claims without departing from the spirit of the invention.

Copies of this patent may be obtained for five cents each, by addressing the "Commissioner of Patents, Washington, D. C."

I claim:

1. The combination with a set of steps, of an extensible step below the bottom step of 50 said set capable of movement toward and away from the bottom step, casings secured to the side members of said set of steps, rack bars slidably mounted within said casings respectively and having the outer ends thereof 55 connected with said extensible step, pinions meshing with said rack bars, means for rotating said pinions to lower and raise said step, lugs on said rack bars respectively below the teeth thereon, lugs in said casings 60 in the path of movement of the first-mentioned lugs and adapted to be engaged thereby to limit the downward movement of the rack bars, and lugs on said rack bars above the teeth thereon adapted to be engaged by 65 the adjacent teeth in said pinions when said rack bars are in lowered position to produce a binding action between the pinions and rack bars to augment the action of said first lugs and prevent accidental downward move- 70 ment of said step when occupied.

2. The combination with a set of steps, of an extensible step normally in engagement with the under surface of the bottom step of 75 said set and capable of movement to lowered position, means for lowering and raising said step, a vertical shaft for operating said means, an operating shaft, driving connections between said operating shaft and vertical shaft, a crank disk on said vertical 80 shaft having one face thereof formed with a depression, a spring actuated locking bolt normally in engagement with said depression to hold said crank disk against turning movement and said step elevated, and a 85 lever connected to said locking bolt and operable to retract the bolt against the action of the spring.

In testimony whereof I affix my signature in presence of two witnesses.

ALFRED ARNT.
